UNITED STATES PATENT OFFICE.

JACOB L. CELANE AND DAVID STEINBERG, OF NEW YORK, N. Y.

ADVERTISING DEVICE.

Application filed December 28, 1921. Serial No. 525,281.

To all whom it may concern:

Be it known that we, JACOB L. CELANE and DAVID STEINBERG, both citizens of the United States, and residents of the city of New York 5 borough of Manhattan, in the county and State of New York, have invented a new and Improved Advertising Device, of which the following is a full, clear, and exact description.

10 The present invention relates to new and useful improvements in advertising devices and it pertains more particularly to devices of this character which are illuminated.

It is one of the primary objects of the invention to provide revolving means moving in the presence of illuminating means to cast shadows of various images upon a reflecting surface in such a manner that the images will move relatively to the reflecting surface.

15 It is a further object of the invention to so construct a device of this character that the revolving member is operated by the heat thrown off from the illuminating means.

20 It is a further object of the invention to form one wall of the fire-proof box with a projecting surface upon which the several objects are projected, said projecting surface being of a transparent nature.

25 With the above and other objects in view, reference is had to the accompanying drawings, in which

Figure 1 is a front elevation of an advertising device constructed in accordance with the present invention;

30 Fig. 2 is a vertical sectional view taken on the line 2—2 of Fig. 1, and

Fig. 3 is a horizontal sectional view taken on the line 3—3 of Fig. 2.

35 Referring more particularly to the drawings, the reference character 5 designates a lamp box, and 6 designates the front wall thereof. This front wall is formed of glass or any other suitable transparent material, and the upper portion thereof designated by the reference character 7 is frosted, the lower portion designated by the reference character 8 being non-transparent for the purpose of carrying any suitable advertisement. The rear wall 9 of the box is in the 40 form of a door hinged as at 10 and provided with a suitable operating means 11 and securing means 12 by means of which the door may be operated and retained in closed position.

45 50 55 Mounted within the box is a socket 13, and carried in said socket is an electric lamp 14.

The feed wires 15 of the electric lamp are led in through an opening 16 in one of the side walls of the box as more clearly shown in Fig. 2. Mounted upon the electric lamp 14 is a revolving member 17, the lower end 18 of which is open. The upper end of this revolving member 17 is closed by a whirligig 19, said whirligig 19 comprising a body portion cut to provide blades or the like 20. At 60 the diametrical center of this whirligig 19, a porcelain bearing member 21 is secured, and said member 21 has a recess 22 adapted to receive the knob or projection 23 of the electric lamp 14. By this construction, the revolving member 17 is mounted upon the electric lamp 14, and the heat of said lamp passing through the whirligig 19 causes the member 17 to revolve.

It is understood that the top wall 24 of 75 the box 5 is provided with an opening 25 to permit of a free circulation of air in order that the revolving member 17 may operate. This revolving member 17 is formed of any suitable transparent material and painted 80 thereon or otherwise affixed thereto is a plurality of objects 26 in simulation of airplanes, ships, and the like. While in the present illustration, these objects are in simulation of airplanes, ships, &c., it is obvious 85 that objects of any character may be carried by the revolving member 17.

The device operates in the following manner:

With the several parts in the position 90 shown in Fig. 2, when the lamp 14 is lighted, the heat therefrom passes through the blades 20 of the whirligig 19, since this is its only outlet from the revolving member 20. As the heat passes through the revolving member 17, and as the several objects 26 thereon pass between the lamp 14 and the front wall 6 of the box, these objects will be reflected on to the upper portion 7 thereof, as shown in Fig. 1, and owing to the revolutions of 95 the revolving member 17, shadows will pass across the upper surface 7 and will give the appearance of natural movement of the various objects picturized.

100 105 110 From the foregoing it is apparent that so long as the lamp 14 is turned on, the member 17 will continue to operate, and the several pictures 26 will be projected upon the surface 7 in rotation as the member 17 revolves. It is obvious, therefore, that the present invention provides a moving sign in which a motor for operating the moving

parts is dispensed with, the heat from the illuminating lamp being employed for the purpose.

Further, it will be noted that by the use 5 of a porcelain, glass, or other hard bearing member 21, the friction between the bearing member 21 and the lamp is greatly reduced, thus increasing the efficiency of the revolving member 17.

10 We claim:

In an advertising device, a lamp box having a glass side wall, said glass side wall having an upper frosted area and a lower opaque area, said opaque area providing display space for advertising matter, a lamp 15

socket carried by the bottom of the lamp box and being of an elongated nature whereby to support a lamp in the rear of the upper posted area of the glass side wall of the box, a lamp carried by said socket, a hood adapted to be rotatably mounted on the lamp carried by said socket, said hood being of a transparent nature and having objects painted thereon which are adapted to be reflected on the frosted area of the glass wall 20 of the box, and means associated with said hood for rotating the same under the influence of the heat generated in said lamp.

JACOB L. CELANE.
DAVID STEINBERG.
